UNITED STATES PATENT OFFICE.

GUSTAF Y. ANDERSON, OF DYEA, ALASKA TERRITORY.

COMBINED SAW JOINTER AND GAGE.

SPECIFICATION forming part of Letters Patent No. 663,822, dated December 4, 1900.

Application filed July 20, 1899. Serial No. 724,519. (No model.)

To all whom it may concern:

Be it known that I, GUSTAF Y. ANDERSON, a citizen of the United States, residing at Dyea, in the Territory of Alaska, have invented a 5 certain new and useful Combined Saw Jointer and Gage, of which the following is a specification, reference being had therein to the accompanying drawings.

This invention relates to combined saw 10 jointers and gages by which crosscut-saws can be more easily and properly filed.

One object of the invention is to provide a device of this character that will permit of the gage-plate being independently, quickly, 15 accurately, and reliably adjusted and firmly held, whereby the former adjustment will serve as a valuable guide in readjusting the gage-plate.

A further object of the invention is to provide 20 the overhanging parts which rest on the saw-teeth points with a smooth and hardened surface to avoid the injurious effects caused by these heretofore rough parts and the friction generally produced while gaging the 25 rakers.

A still further object of the invention is to have the overhanging parts dressed and made smooth throughout their entire inner sides 30 and connected with the frame or body at their extreme outer and inner ends to form a clear, distinct, unbroken longitudinal surface and open spaces opposite the cutting-teeth, through which the points of the teeth can be clearly viewed on a level with the inner side of said overhanging parts, thus providing 35 a straight-edge by which the uniform height of the saw-teeth can be easily ascertained and determined.

A still further object of the invention is to 40 provide a saw-jointer of such construction as to enable the file-clamp to be centrally held in close contact with the frame for preventing wabbling and to hold the file in true position when in use.

The invention consists in certain novel 45 features and details of construction and arrangement of parts, as hereinafter fully set forth, illustrated in the drawings, and pointed out in the claims.

In the drawings forming a part of this specification, Figure 1 is a perspective view of an 50 implement for fitting up crosscut-saws con-

structed in accordance with my invention. Fig. 2 is an elevation looking at the other side of the implement. Fig. 3 is a sectional view on the line xx of Fig. 2. Fig. 4 is a sectional view on the line yy of Fig. 2. Fig. 5 is an edge view. Fig. 6 is a sectional view showing a modification of the invention. Fig. 7 is a side elevation of the central portion of the implement. Fig. 8 is a central cross-section on the line zz of Fig. 7.

Similar characters designate corresponding parts in the different figures of the drawings.

In carrying out my invention I cast or otherwise form the frame of the body 1 of open-work to reduce the weight of the implement, and at opposite sides of this body are formed projecting flanges 2 and 3, the lower flanges 3 being partly cut away, so as to still further 60 reduce the weight of the implement. The central portion of the frame is enlarged to form a gage-post 4, which extends a short distance above the top flange 2 and in which is a round, preferably drilled, opening 5, that 70 extends to within a short distance of the lower end of said post.

Upon the flange 2 are formed posts 6 and 7, the latter being at the ends of the frame, while posts 6 are at intermediate points. The tops 80 of said posts are all in exact longitudinal alignment and form seats for the straight-edge sections. Extending from each of the outer posts 7 to the adjoining post 6 is a straight-edge section 8, said sections being secured to 85 the posts by machine-screws, which are let into the same through the straight-edge sections, said sections being of hardened steel, smooth and polished throughout on their entire inner surface, so as to leave clear unobstructed spaces under the plates or sections 90 by which the teeth can be clearly viewed on a level with the inner sides of the overhanging plates or sections for ascertaining and determining the uniform height of the teeth. 95

It may be here stated that while the plates or straight-edge sections might be made integral with the frame and dressed off to suit requirements separate plates are preferable to more easily obtain the several objects in view, and by placing a thin piece of metal between the plates and each of the inner posts of exactly the same thickness and by the further use of paper said plates can be ad-

justed to fit the curve of the saw, so as to rest evenly on the saw-teeth points, and when this is not done a small space should occur between the outer teeth and the straight-edge 5 when the teeth are properly jointed, as shown in Fig. 2, owing to the curve in the saw, as will be readily understood.

In connection with the sectional straight-edge hereinbefore described between the intermediate posts 6 is located a gage-plate 10, having the usual slot 11 therein, said gage-plate being provided with a shank 12, which passes partly through the opening 5 in the gage-post. The shank being of considerable 10 length will permit the lower end to be engaged by an adjusting-screw 13, having a head 14 and adjoining collar 15, said adjusting-screw being inlaid in a suitable groove or recess 16, that may be formed on either side of the frame 15 and in which the screw fits snugly between the head and the collar, thus preventing the screw from moving either up or down when it is turned. The said screw extends into a threaded opening 17 in the end of the shank 20 25 12, and the gage-plate can be accurately adjusted parallel with the straight-edge sections by turning said screw. To prevent lateral movement, the gage-plate is recessed to embrace guide-flanges 18, formed on the posts 6. 30 The adjustment of the slotted gage-plate is held by means of a set-screw 19 passing through a screw-threaded perforation in lug 20 and engaging the shank in the gage-post.

On the side of the implement shown in Fig. 35 1 is located the jointer and side file. The dotted line *a* shows the position of the file as held for jointing the points of the saw-teeth, and the dotted line *b* shows the position of the side file as held for dressing the sides of 40 the saw-teeth points. On one side of the posts 7 are formed projections 21, on which a part of the seats for the plates 8 extend, and said projections are provided with true bearings at right angles with the outer edges of 45 flanges 2 and 3. A cylindrical and centrally-located lug 20 projects laterally from the frame and has a horizontal threaded opening therein, and beneath said lug in one form of the device is another lug 33, having a vertical 50 screw-threaded opening for a screw 32, adapted to operate a file-clamp 22. Said clamp has a longitudinal slot divided by a cross bar or brace 24, and the lower end of the clamp has a notch on the inner side to permit it to rest closely against the frame when 55 placed over the lugs and screw and is also provided with right-angular projections at each end and a bearing-face 23 at the top, and another bearing against which a cam 25, 60 revolving on the cylindrical lug 20, will contact for operating said clamp. Thus it will be seen that the file-clamp may be operated either with a cam or a screw and that either end of said screw might be made to operate 65 against the clamp, as shown in Fig. 1. It will, however, be understood that both modes of operation are not required in the same tool

or combination of tools. The height of the lug 20 should correspond with the thickness of the file-clamp, as shown in Fig. 8, or with 70 the combined thickness of the clamp and the cam, as shown in Figs. 4 and 6, which depends on the mode adopted. A washer 26 is preferably used between the lug and the head of the binding-screw 19, which washer has a larger circumference than the lug, the binding-screw being of the right length to permit 75 this. The clamp and the cam are placed between the frame and the washer, the lug passing through the same, and the clamp is held as close against the frame as its sliding movement for securing and releasing the file will permit by the thickness of the washer employed, and thus prevents wobbling of the clamp. Two small guide-flanges 27 have also 80 been provided to further hold the clamp in place, as shown in Fig. 1. By placing the file between the bearings on projections 21 and bearing-face 23 on the top of the clamp, as shown in Fig. 1, and pressing on the lower 85 end of said clamp and turning the cam, which has an offset on which to place the finger, a long and even curve in the file can be obtained, the resiliency of the file holding the adjustment. The file will not come in contact with the cam, and thereby injure it, and is held true right angularly with the outer edges of flanges 2 and 3, which will bear 90 against the saw-blade while manipulating the device. This mode of operation is very convenient, and the cam revolving on a laterally-projecting lug on the frame will not loosen the screw by which it and the adjustment of the gage-plate is held. 95

By having the usual vertical flanges 28 100 near the ends of the frame partly cut away, so as to form a recess for the file and a right-angular projection on the lower end of the clamp, the side file for removing the feather-edge or burs from the side of the saw-teeth 105 points can be fastened in the same manner as that hereinbefore described.

The form illustrated in Fig. 6 is substantially the same as that hereinbefore described, except that instead of the groove or 110 recess 16 it has a screw-threaded perforation 30 in the lower end of the gage-post connecting with the opening 5, the plain adjusting-screw 31 being placed in the screw-threaded perforation and turned until it abuts squarely up 115 against the end of the shank. By pressing with the finger on the gage-plate while adjusting the same the gage-plate can be quickly and fully as accurately adjusted as in the construction of the implement whereby the screw 120 having the collar is used. 125

By reference to Figs. 7 and 8, it will be seen that in this form the cam 25 is omitted and the screw 32 and lug 33 adopted. The file-clamp 22 is of the same form and holds 130 the file in both positions and is itself held against the frame in the same manner as has been hereinbefore described.

From the foregoing description it will be

noted that I provide a tool adapted to a variety of purposes independent of each other which is simple, cheap, and effective, particularly in the raker-gage, owing to the manner in which 5 its gage-plate is adjusted and held, and also in the removal of all such parts as have heretofore prevented the saw-teeth points from being clearly viewed on a level with the overhanging parts which rest thereon, whereby a 10 sectional straight-edge is formed with which to quickly locate such saw-teeth as might be too long or too short. The long teeth can be touched with the file until they are of the right length and the short teeth marked on their 15 bevel by a stroke of the file and a coarser point filed thereon. In this way less filing is required, thereby saving time, files, and needless wear upon the saw and enabling the user thereof to always keep the saw-teeth in proper 20 shape.

Having thus described my invention, what I claim as new, and desire to secure by Letters Patent, is—

1. In a saw-gage, in combination, a frame 25 having a series of posts presenting a horizontal line of bearings with spaces between the outer posts, a gage-plate embracing flanges on the inner posts and having its top face dressed in a true line with said bearings and 30 provided with a long, round shaft extending through a drilled opening in the enlarged portion of the frame in which it fits snugly so as to produce a true up-and-down movement, an adjusting-screw inserted through a threaded 35 opening in the lower part of the frame, and bearing against the end of the shank and capable of adjustment independently of any other part of the device, and a binding-screw extending through the frame at a right angle 40 to the shank for holding the latter fast, substantially as described.

2. In a saw-gage, in combination, a frame,

a series of posts forming a horizontal line of bearings, a gage-plate and means for adjusting the same, and independent sets of 45 plates presenting a hard and smooth surface throughout their entire length and forming a sectional straight-edge beneath which are left spaces through which the points of the cutting-teeth can be simultaneously viewed, 50 substantially as described.

3. In a combined gage, straight-edge and jointer, in combination, a frame, a series of posts presenting a true line of bearings for the plates secured thereon, and forming a 55 straight-edge in which spaces are left through which the cutting-teeth may be simultaneously viewed, a gage-plate having a round shank extending through a correspondingly-shaped opening in the frame, an adjusting- 60 screw having a collar working in a groove near the lower edge of the frame, a laterally-projecting lug on the frame above the plane of said groove, a clamp or slide embracing said lug and having file rests or projections 65 extending at right angles thereto at its upper and lower ends, and a cam for operating and holding said clamp or slide, substantially as described.

4. In a saw-jointer, in combination, a frame 70 provided with laterally-projecting lugs 20 and 33, a file-clamp having two slots divided by a cross-bar, a set-screw 19 passing through one of the slots of the file-clamp into the lug 20 for holding the file-clamp in its place, and 75 means for operating the file-clamp up and down, substantially as described.

In testimony whereof I affix my signature in presence of two witnesses.

GUSTAF Y. ANDERSON.
